Primary Examiner — T. Chase Nelson(74) *Attorney, Agent, or Firm* — Marshall A. Lemer; Marvin H. Kleinberg; Kleinberg & Lerner, LLP(57) **CLAIM**

The ornamental design for a shoe periphery and bottom, as shown and described.

DESCRIPTION

FIG. 1 is a perspective view of a first exemplary embodiment of a shoe periphery and bottom in accordance with my new design.

FIG. 2 is a left side view thereof;

FIG. 3 is a right side view thereof;

FIG. 4 is a top plan view thereof;

FIG. 5 is a bottom plan view thereof;

FIG. 6 is a rear elevation view thereof; and

FIG. 7 is a front elevation view thereof.

FIG. 8 is a perspective view of a second exemplary embodiment of a shoe periphery and bottom in accordance with my new design.

FIG. 9 is a left side view thereof;

FIG. 10 is a right side view thereof;

FIG. 11 is a top plan view thereof;

FIG. 12 is a bottom plan view thereof;

FIG. 13 is a rear elevation view thereof; and,

FIG. 14 is a front elevation view thereof.

Broken lines showing the remainder of the shoe in the figures are for illustrative purposes only and form no part of the claimed invention.
